UNITED STATES PATENT OFFICE.

WILLIAM E. KAWALLE, OF OAKLAND, CALIFORNIA.

MITER-BOX.

1,115,832.

Specification of Letters Patent.

Patented Nov. 3, 1914.

Application filed October 15, 1913. Serial No. 795,264.

To all whom it may concern:

Be it known that I, WILLIAM E. KAWALLE, a citizen of the United States, residing at Oakland, in the county of Alameda and 5 State of California, have invented new and useful Improvements in Miter-Boxes, of which the following is a specification.

This invention relates to improvements in the construction of miter-boxes, particularly 10 to the type described and illustrated in my co-pending application, filed October 8, 1912, Serial No. 724,616.

The object of the invention is to provide a simple, reliable, easily adjusted miter-box 15 which is so constructed that the molding supporting angle-plates will move in unison, one with the other, to the extent of at least 45° on either side of a straight line.

Another object of the invention is to provide 20 a locking mechanism whereby the molding supporting plates may be quickly and simultaneously locked the moment the desired cutting angle has been secured.

Another object of the invention is to provide 25 a swivel attachment which will permit the miter-box to be turned as a unit into any desired position with relation to its supporting base.

Further objects will appear hereinafter. 30 The invention consists of the parts and the construction and combination of parts as hereinafter more fully described and claimed, having reference to the accompanying drawings, in which,—

35 Figure 1 is a plan view of a miter-box. Fig. 2 is a perspective view of one of the turnable guide rings. Fig. 3 is a perspective view of a drum. Fig. 4 is a side view of the miter-box. Fig. 5 is a vertical central 40 section through the turning mechanism of the guide box. Fig. 6 is a plan view of the swivel base on the line $x-x$ of Fig. 5.

Referring to the drawings: A indicates a base plate adapted to be secured in any suitable manner to a work-bench or like support. Turnably mounted upon the base plate is a swivel base 2, and formed on the lower portion or edge of same is a pair of projecting flanges 3, which are so positioned 45 as to be engaged by a pair of retaining guide lugs 4 formed on the main base plate A; the space 5 between the projecting flanges 3 is just sufficient to permit the swivel base to be dropped between retaining lugs 4, before turning same into the interlocked position shown in Fig. 6.

Secured upon the swivel base 2, in a concentric position with relation to same, is a drum 6 provided with a pair of annular flanges 7 and 8 which project out a sufficient distance from the face of the drum to form bearings for a pair of turnable rings 9 and 10, and a pair of turnable guide rings 11 and 12. The main bearing drum 6, upon which the several rings just mentioned are supported, is secured to the swivel base 2 by a clamping plate 13 and screws 14 which secure the clamping plate and drum with relation to the swivel base 2. The clamping plate 13 is provided with an annular outwardly projecting flange 15 which retains the rings 9 and 11 in position upon the annular flange 7; the lower rings 10 and 12 are similarly secured in position by the annular flange 8, while the swivel base 2 acts 75 as a bearing for the two lower rings.

Suitably secured to the rings 9 and 10, or formed integral with same, is a pair of beveled gear segments 9' and 10', and turnably mounted upon a stud shaft 16 secured 80 in the drum 6 is a beveled pinion 17, which is so positioned as to intermesh with the upper and lower gear segments 9' and 10'. Any turning movement exerted upon one ring or another will thus be equally and simultaneously transmitted to the opposite ring, causing these to move in unison but 85 in opposite directions.

18 and 19 indicate the main horizontally positioned supporting plates of the miter-box, upon which are carried vertical guide plates 20 and 21. The guide plates 20 and 21 are here shown as detachably mounted, said detachable mounting being secured by providing outwardly projecting lugs 22 and 90 23 on the upper and lower plates, respectively, through which a taper pin 24 may be passed to temporarily secure the plates together. One of the horizontal plates, as 18, is secured to the upper turnable ring 9, as 95 100 at 25, and to the lower guide ring, at 26, through a supporting bracket 27 which is secured to the outer end of the plate 18 at 28; further connection being provided by the screw 29. The plate 18, being secured to the 105 rings 9 and 12, will thus always move in unison with same, while the opposite plate 19, which is secured to the upper guide ring 11, as at 30, and to the lower ring 10, as at 31, through the medium of a bracket 32 110 and a screw 33, will naturally move in unison with these rings, opposite movement of

one plate with relation to the other being secured by providing gear segments 9' and 10' and intermediate interlocking pinning 17. It can thus be seen that the movement of one plate will always be transmitted to the opposite plate as the spacing of the teeth, and the pitch line of same is constant, a uniform movement of the plates in relation to each other will thus always be secured.

10 For the purpose of quickly locking the plates 18 and 19 the moment the desired cutting angle has been secured, the following locking mechanism has been provided: Referring to Figs. 1 and 4, 34 indicates a brake-shoe pivotally mounted upon the lower side of the plate 19, as at 35. Turnably mounted upon a pin 36, also secured to the lower side of the plate 19, is an eccentric member 37 provided with an outwardly extending thumb projection 38. The operation of the locking mechanism is accomplished by swinging the eccentric in the direction opposite to that of arrow *a*; the eccentric is thus turned in a position where it will engage 25 with the outer end of the brake-shoe 34 and cause this to bear against the rings 9 and 11 with sufficient force to lock these with relation to the plate 19. The locking of the two rings 9 and 11 with relation to each other 30 consequently prevents any movement of the rings 10 and 12. The plates 18 and 19 are thus simultaneously locked through the medium of the rings 9 and 11, and this may be quickly accomplished regardless of the position 35 of the plates 18 and 19, as it only becomes necessary to swing the eccentric about its pivot 36.

Projecting through a slot 39, formed in the swiveled base 2, is a horizontally disposed bar 40, upon the outer ends of which are slidably mounted a pair of blocks 40'. Secured in the blocks 40' is a pair of vertically disposed guide rods 41-42, and slidably mounted upon the vertically disposed 45 rods 41-42 are saw guide frames 43, through which the saw may be inserted and guided while cutting the moldings or similar objects within the miter-box.

It will be understood that each end of 50 the bar 40 is provided with blocks 40' and upwardly extending rods 41 and 42 upon which are slidably mounted the guide frames 43, and that the saw may be inserted through same to keep this in perfect alinement with 55 relation to the center of the miter-box. Set screws 44 have been provided, as indicated in Fig. 6, for the purpose of keeping the guide frames in perfect alinement with relation to the center of miter-box. Both of the 60 vertically disposed rods 41 are slightly indented or notched, as indicated at 45, to permit a spring-actuated latch 46 to snap into this depression and retain the saw in an elevated position with relation to the miter-box when not in operation. Very slight

pressure is, however, sufficient to depress the frames 43 into operative position with relation to the molding or other material placed within the box.

Referring to the perspective view, Fig. 2, 70 it will be seen that the guide ring 12 has formed on one side a lateral projection 12'. This is provided for the purpose of permitting the bracket 27 to be secured to same. The upper guide ring 11 is provided with a 75 similar extension 11' to which the angular plate 19 is secured.

The miter-box constructed as here shown is simple in construction, reliable in action and may be quickly dismantled for packing 80 or shipping purposes when so desired. The plates 18 and 19 may be quickly removed by simply unscrewing the screws 29 and 33. This permits the plates 18 and 19, with connected brackets 27 and 32, to be released with relation to the different rings. The bar 40, together with the upright rods 41-42 and saw guide frames 43, may be also quickly removed by simply slackening up the set screws 44. The different extensions, such as the plates 18 and 19 and guide frames 43 may thus be quickly removed, or assembled, as the case may be, without disturbing the main locking mechanism and gearing mounted on the base A. Similarly by providing 90 the swivel base 2, it becomes possible to swing the miter-box into the most convenient position with relation to its support and the operator. Furthermore, a much truer cut 95 may be obtained when using a swivel base, as any wobbling of the saw blade will be transmitted to the swivel base, thus permitting a straight movement of the saw between the guide frames 43.

The materials and finish of the several 105 parts of the miter-box are such as experience and judgment of the manufacturer may dictate.

The upper surface of the clamping plate 110 may be graduated, as at 48, thus permitting the operator to set the supporting plates at any desired angle.

Having thus described my invention what I claim and desire to secure by Letters Patent, is:

1. The combination in a miter-box of a 115 swivel base, a bearing drum secured to the swivel base, a pair of upper and lower rings turnably mounted on said drum, supporting plates secured to said rings, means for transmitting uniform movement from one plate to another, and a brake-shoe directly engageable with the rings to lock the rings and plates against movement.

2. In a miter-box, the combination of a 125 swivel base, a bearing drum on said base, a pair of supporting plates turnably mounted on the drum, segmental rack sections on said plates, a pinion journaled on the drum intermeshing with said rack sections, an an-

nular friction face secured to one of the supporting plates, a brake-shoe engageable with the periphery of said friction face, and a lever operated eccentric engageable 5 with the brake-shoe.

3. In a miter-box, the combination of a swivel base, a bearing drum on said base, upper and lower rings journaled on the drum, segmental rack sections formed on 10 said rings, a guide ring mounted on the drum and above the upper rack-carrying ring, a guide ring mounted on the drum and below the lower rack-carrying ring, a supporting plate secured to the upper rack- 15 carrying ring, a bracket connecting said plate with the lower guide ring, a supporting plate secured to the upper guide ring, a bracket connecting said plate with the lower rack-carrying ring, a pinion journaled on 20 the drum intermeshing with the racks, a brake-shoe engageable with the outer face of the upper rack-carrying ring and guide ring, and means for operating said brake-shoe.

25 4. The combination in a miter-box of a swivel base, a bearing drum secured to the swivel base, a pair of upper and lower rings turnably mounted on said drum, supporting plates secured to said rings, and a brake- 30 shoe engageable directly with the rings to lock the rings and plates against movement.

5. In a miter box, a swivel base, a drum

on said base having an upper flange and a lower flange, a lower guide ring on the base and a lower toothed ring superimposed on 35 the guide ring and arranged between said base and lower flange, an upper toothed ring and an upper guide ring superimposed thereon and arranged on said upper flange, a pinion meshing with each of the toothed 40 rings, a horizontal plate connected to the upper toothed ring, means to connect said plate to the lower guide ring, a second horizontal plate connected to the upper guide ring, and means connecting the second horizontal 45 plate to the lower guide ring.

6. In a miter box, a central drum, means for rotatably mounting the drum, a pair of horizontal plates, means connected to each plate and rotatably disposed over the drum 50 for independently mounting each plate on said drum, means to drive said plate mounting means in unison, an annular friction face on one of the plate mounting means, and brake mechanism for engagement with 55 said friction face.

In testimony whereof I have hereunto set my hand in the presence of two subscribing witnesses.

WILLIAM E. KAWALLE.
